CAMEL COMPANY, OF CHICAGO, ILLINOIS, A CORPORATION OF ILLINOIS

LATCHING MECHANISM FOR HOPPER DOORS

Application filed April 29, 1929. Serial No. 353,806.

This invention relates to latching mechanism for hopper drop doors.

In many instances, the hoppers on cars are divided at the center sill of the car, and in the past it has been the practice to span the gap by some reinforcing arrangement which causes both doors to open and close together. This latching arrangement was very heavy and clumsy and more or less difficult to operate, so that it did not give complete satisfaction.

According to this invention, the hopper doors are securely latched by means that draw the hopper doors into tight engagement with the wall of the hopper, and at the same time ties the end walls of the hopper together. The invention also contemplates means for securing the latching mechanism in operative position against working loose or accidental operation.

The invention comprises the novel structure and combination of parts hereinafter described and more particularly pointed out and defined in the appended claims.

In the accompanying drawings which illustrate a preferred embodiment of this invention and in which similar reference numerals refer to similar features in the different views:

Figure 1 is a fragmentary top plan view of a hopper car illustrating one of the hoppers.

Figure 2 is a sectional view taken upon the line II-II of Figure 1.

Figure 3 is a fragmentary elevational view showing parts in section taken upon the line III-III of Figure 2.

Figure 4 is an enlarged elevational view of one of the hoppers.

Figure 5 is an enlarged sectional view taken upon the line V-V of Figure 4.

As shown on the drawings:

In the drawings, there are shown fragments of a hopper car which is divided at its central sill 1 into two hoppers 2 and 3 respectively. These hoppers are closed by hinged doors, which are maintained in closed position according to this invention. The doors which are indicated by the reference numeral 4 are hinged at their upper ends by hinges 5. Only one of these doors is fully

illustrated, since the two are similar in all respects.

Adjacent the lower margin of the door 4, there is pivoted a latching bar 6. It will be noted that this bar is pivoted to the door by means of a pivot pin 7 which extends through a casting 8 which is secured substantially centrally of the door. This casting is provided with a passage or opening therethrough to receive the latch bar 6 and to allow the same to freely swing upon its pivot. The latch bar itself may assume any convenient form. In the present instance, it is illustrated as consisting of a Z-bar. Upon the ends of the hopper are secured suitable keepers 10, which have flaring edges 10a as shown in Figure 2, in order to draw the ends of the latch bar inwardly.

It will be noted that the flaring edges 10a are upon inwardly directed flanges which form lips 10b as clearly shown in Figure 2. The latch bar 6 is provided with laterally projecting lips 6a upon its ends which engage behind the lips 10b for tying the ends of the latch bar together.

The aforementioned casting 8 is provided with an arm upon which a cam lever 12 is pivoted intermediate its ends. The lower end of the cam lever is curved so that when it is swung into the position shown in Figure 4, the lower end thereof will engage the latch bar 6 at a point beyond dead center. The curved end of the lever will also engage the casting 8 and prevent the lever from swinging in a clockwise direction. To this end the arm is provided with a bifurcation 11 in which the lever 12 is pivoted. This curved lever will effectively latch the bar 6 in door closing position and prevent the bar 6 from being swung until the cam lever 12 is swung into the dotted line position shown in Figure 3.

In the operation of the foregoing mechanism, the operator will first swing the lever 12 into dotted line position as shown in Figure 3 when it is desired to open the hopper door. After this has been done, the operator will swing the bar 6 in an anti-clockwise direction to remove the ends from beneath the flanges on the keeper 10. This movement of the latch

bar will unlatch the door and it may be readily opened. In closing the door, the operator will swing the door forwardly while the bar 6 is in the dotted line position shown in Figure 3. When the door is in substantially closed position the operator will swing the latch bar 6 into horizontal position to engage the ends thereof under the keeper 10. After this is done, the cam lever 12 may be swung into the position shown in Figure 4 for locking or securing the latch bar 6 against accidental swinging movement.

This locking mechanism is very simple in structure and operation and effectively maintains the door in closed position. At the same time the latch bar securely ties the ends of the hopper together. On account of the cam lever 12 which firmly latched the bar 6 in horizontal position, it is impossible for the same to work loose and allow the door to open.

We claim as our invention:

1. In a car having a hopper, a door for closing said hopper, a swingable latch bar pivoted intermediate its ends to said door, keepers secured to the ends of the hopper for receiving the ends of the latch bar, said keepers and latch bar having overlapping parts to tie the ends of the hopper together and a cam lever pivoted to said door for engaging said latch bar for maintaining the same in horizontal position.

2. In a car having a hopper, a door hinged to said hopper, a casting secured centrally of the lower margin of said door, a latch bar pivoted intermediate its ends to said casting, keepers upon the ends of the hopper for receiving the ends of said latch bar, a cam lever pivoted to said casting for engaging the latch bar and securing the same in door closing position.

3. In a car having a hopper, a door hinged to one side of said hopper, keepers upon the ends of said hopper, a latch bar pivoted intermediate its ends to said door and swingable for engaging behind said keepers, said keepers and latch bar having overlapping lips for preventing the ends of the hopper from spreading and a lever pivoted to said door for engaging said latch bar for maintaining the same in door closing position.

4. In a car having a hopper, a door hinged to one side of said hopper, keepers upon the ends of the hopper, said keeper having overhanging lips with sloping edges, a latch bar pivoted to said door intermediate its ends for engaging said keepers and having lips for engaging behind the overhanging lips of said keepers and means for maintaining said latch bar in door closing position.

5. In a car having a hopper, a door hinged to one side of said hopper, keepers upon the ends of the hopper, a latch bar, a casting having a passage therethrough secured to said door, a pivot extending through said casting, a latch bar and door for pivoting said latch

bar, said casting having a laterally extending arm, a cam lever pivoted to said arm and adapted for engaging said latch bar when the same has been swung beneath said keeper for maintaining the same in such position, said lever engaging said casting when said lever is swung into latching position.

In testimony whereof we have hereunto subscribed our names at Chicago, Cook County, Illinois.

KENNETH J. TOBIN.
AXEL WASBERG.
